CLAIM

The ornamental design for a tablet filling machine, as shown and described.

DESCRIPTION

FIG. 1 is a front elevational view of the tablet filling machine;
FIG. 2 is a rear elevational view of the tablet filling machine;
FIG. 3 is a left side elevational view of the tablet filling machine;

FIG. 4 is a right side elevational view of the tablet filling machine;

FIG. 5 is a top plan view of the tablet filling machine; and,
FIG. 6 is a bottom plan view of the tablet filling machine.

The broken lines in the drawings depict unclaimed environment subject matter.
